UNITED STATES PATENT OFFICE.

FORTUNÉ HEGLE, OF NEW YORK, N. Y.

DESIGN FOR ORNAMENTING THE WRISTBANDS OF GLOVES.

Specification forming part of Design No. 5,809, dated April 23, 1872.

SPECIFICATION.

Specification describing a Design for Ornamenting Kid Gloves, designated "The Péline Kid Glove," invented by FORTUNÉ HEGLE, of the city, county, and State of New York.

The nature of my design is fully represented in the accompanying drawing forming a part of this specification, in which the same letters of reference, wherever they occur, refer to like parts.

Figure 1 represents the back of the glove; Fig. 2, the front of the same; Fig. 3, a sectional view of the edge of the bracelet and wristband of the glove.

Letter A represents the body of the glove, having a serrated scallop shaped or edged wristband, B, of about one inch in depth or width, attached to the wrist of the glove. Intervening between the wristband and wrist of the glove is stitched a rolled or folded welt, C, and, at the same operation, a band or bracelet, D, of about half an inch wide. The upper edge of the band or bracelet is bound with a narrow strip or edging, E, of corresponding width with the welt C. Upon the face of the band D is secured a trimming composed of two separate strips, F and G. These are secured thereon at the same time of putting on the binding E. The lower edges of these two strips of trimming are serrated and scalloped. The lowermost one F covers about two-thirds of the depth of the band D, while the uppermost

one G covers but about half of F, thus each of the strips of trimming leaving a margin of background to give relief to the trimming and at the same time a pleasing effect in contrast to the welt C and binding E. It will be observed that the band D is only attached to the body of the glove or wrist by its lower edge, thus leaving its upper edge detached or separate from the wristband. The object of this is to give a better effect to the design and the appearance of a bracelet, and at the same time avoid the appearance of being simply stamped or printed on the wristband of the glove. It will be obvious that the omission of either the welt C or binding E would not greatly affect the harmony of the design; and, though I prefer to use both of them, yet, in the event of parties using but one of them with a view to a technical avoidance of my design, I desire it to be understood that my design is for the use of one or both of the parts, to wit: the welt C and binding E, in connection with the band D, trimming F and G, and wristband B.

What I claim, therefore, as my invention is—

The design for ornamenting the wristbands of kid gloves, made substantially as hereinbefore set forth and shown.

FORTUNÉ HEGLE.
